JUSTIFIED TYPE-BAR.

No. 922,632.

Specification of Letters Patent.

Patented May 25, 1909.

Application filed March 22, 1899, Serial No. 710,029. Renewed August 8, 1908. Serial No. 447,590.

To all whom it may concern:

Be it known that I, FRANCIS H. RICHARDS, a citizen of the United States, residing at Hartford, in the county of Hartford and State of Connecticut, have invented certain new and useful Improvements in Justified Type-Bars, of which the following is a specification.

This invention relates to justified type-bars and a method of making the same, the main object being to effect the justification or proper spacing of a plurality of separate types formed on a type-bar, this justification being accomplished by reducing the body of the bar in a substantially uniform manner throughout its length to elongate the bar from a normal unjustified length to a fixed justified length corresponding to the width of any given column of matter which it may be desired to compose.

In practice when type-bars are formed containing different groups of words or characters the different type-bars vary in length if the types are formed thereon without justifying them, and hence such type-bars in order to bring them up to a given standard of length must be elongated by different amounts, which amounts will of course be the difference between the fixed justified length representing the width of a column of matter and the lengths of the shorter unjustified type-bars. Hence in practicing my improvements in the art of justifying type-bars, although the bars will be reduced in cross-section in a substantially uniform manner throughout the lengths thereof yet the reduction of the cross-section of some of the bars will be less than for others.

The reduction of the cross-section of an unjustified type-bar, for the purpose of elongating the latter and making it of a predetermined standard length, may be effected in different ways, but I prefer to reduce the cross-section of such a bar by subjecting the body portion thereof to uniform compression substantially throughout its length, this compression being effected preferably by rolling the body of the bar by means of one or more reducing-rollers, which will operate upon the whole length of the side of the bar and reduce the cross-section of the body portion to the same extent at all points in the length thereof.

My present improvement may be employed for the purpose of justifying type-bars of different kinds, but it is intended particularly for the justification of a type-bar on which the types are preferably formed on one of the long edges thereof, in such a manner as to be separated from one another by division-spaces extending to the bases of the types, and hence said types are interconnected with one another except where their bases merge into the body of the bar. A type-bar of this construction is peculiarly adapted to be justified according to my present invention, as the types are separated from one another, and the body of the type-supporting bar from which they rise may be reduced in cross-section below the types substantially uniformly throughout its length without distorting the types previously formed on such bar. The reason for this is that as the types are small members and have extremely small bases as compared with the length of the body of the bar, and as these small members are entirely separated from one another laterally, the body of the bar may be reduced in a uniform manner—as by compressing it—and if only the bar is so reduced or compressed—as is the case in the present instance—the effect of such a reduction or compression of the large body portion will not extend above the base-line of the types, and hence the result will be to widen the spaces between such types and thus adjust their positions, or justify them in the line, without elongating or otherwise distorting the types themselves.

In the drawings accompanying and forming part of this specification, Figure 1 is a plan of an unjustified type-bar suitable for the purpose of justification in accordance with my present invention. Fig. 2 is a side elevation of the same. Fig. 3 is an end elevation of the same. Figs. 4 and 5 are respectively a plan and a side elevation illustrating the appearance of the same type-bar after it has been reduced in cross-section and justified in accordance with my invention. Fig. 6 is a side elevation of a pair of reducing-rollers for elongating or drawing out an unjustified type-bar. Fig. 7 is a front elevation of the same. Fig. 8 is a plan of a group of unjustified type-bars of different lengths; and Fig. 9 is a similar view

2
illustrating the appearance of the same after being elongated to form type-bars of uniform length.

Similar characters designate like parts in 5 all the figures of the drawings.

The unjustified type-bars which are to be afterward subjected to reduction for the purpose of justifying them may be produced by forming the successive types on type-bar 10 blanks of any suitable lengths and afterward removing or cutting off those portions of the blanks on which types are not formed; but I prefer to form these types on a continuous type-bar blank or rod from which 15 unjustified type-bars of suitable lengths may be severed as desired after the formation of a suitable number of types on the continuous rod, as indicated in Fig. 1.

The body of each type-bar is designated 20 herein in a general way by B, and the types formed thereon by 94. These types may be formed in any suitable manner, but preferably substantially as shown and described in the application of Darien W. Dodson, 25 hereinbefore mentioned—that is to say, each type may be formed on the edge of a type-bar by a suitable die in such a manner as to leave a space, such as 91, between it and the adjacent type, this space extending down to 30 the base-line of the type, which base-line will usually be common to a whole series or line of types located on the edge of the type-bar.

In the prior Dodson application the manner in which the types are formed is, briefly 35 stated, as follows: A type-bar segment is first separated from the body of the bar by making a cut, such as 91, in the edge of the bar, and then beveling off the sides of the 40 type-bar blank, as at 92 and 93, after which a suitable die may be brought down on to the type-blank segment and the proper type, 94, formed thereon, some of the metal displaced by compression being forced into the 45 division-space 91 to partly fill the latter. Obviously, now, the types so formed will be entirely separated from one another from their faces to their bases, and as the sides of the lower portions of the types are beveled 50 off, as shown at 92 and 93, and lie within the walls of the body, the parallel flat sides of the body portion B may be subjected to compression to reduce the cross-section of such body portion without distorting the 55 previously-formed types themselves. In fact the opposite sides of the body of this type-bar may be subjected to compression throughout their lengths and the body portion of the bar correspondingly reduced 60 without compressing the sides of the type, and the effect of the compression will be carried substantially no farther than the base-line, which line is indicated herein by 96. Of course it should be understood that 65 this uniform reduction of the cross-section

of the body B of the type-bar may be effected in other ways, but I deem it desirable to accomplish it by rolling the bar, and hence I have illustrated herein a pair of reducing-rollers r—r', between which the unjustified 70 type-bar may be subjected to compression to reduce the body of the bar in cross-section and to correspondingly elongate it to the desired amount. The extent of this elongation will in all cases be determined by the 75 length of the unjustified type-bar and will be greater for short unjustified bars than it will be for longer ones. In every case, however, whether the bar is to be reduced in cross-section little or much the amount of 80 the reduction and consequent elongation will be regulated to bring the finished justified type-bar in every case to a predetermined standard of uniform length.

The difference between the appearance of 85 an unjustified type-bar and a justified type-bar is clearly illustrated in Figs. 1, 2, 4, and 5, by referring to which it will be seen that the division-spaces 91 in Figs. 1 and 2 are not so wide as in Figs. 4 and 5, in which by 90 reason of the elongation of the type-bar the types have been somewhat spread out, and hence the spaces between them widened. This difference is indicated clearly in Fig. 4, 95 in which the width of each space is represented by two transverse lines, whereas in Fig. 1 the single line shows that although the types are separated they are very nearly in contact. Moreover, in Fig. 1 the sides of the body portion B are clearly distinguished 100 from the upper edges of the oblique faces 92 and 93, whereas in Fig. 4 a single line at each side of the bar indicates that after the compression of the type-bar the side faces of the body and the upper edges of these 105 blank-faces are substantially merged. Thus the extent to which the length of each bar is increased, is proportionate to the amount that that particular bar falls short of the 110 width of the column and the space between each pair of consecutive types in the justified bar will bear substantially the same relation to the space as it was before justification as the length of the justified bar bears to the unjustified bar. That is to say, all 115 the spaces will be increased in substantially the proportion that the unjustified bar is elongated when brought to the final or justified condition. In setting up a series of 120 these improved type-bars in a column the column will of course be shortened, as indicated in Fig. 9, by an amount corresponding to the aggregate reduction of the bars in thickness, as will be evident by comparing 125 Figs. 8 and 9. While this reduction in the length of the column when a large number of the justified bars are assembled over the corresponding length of the column before justification may be appreciable, yet the 130 operation or operations to which each short

bar is subjected for the purpose of increasing or equalizing its length to the width of the column does not materially change the height of the typebar since almost all of the 5 mechanical effect on the bar is confined to the stretching of it endwise as the result of reducing by a small amount the thickness of the bar body, that is, the portion of the typebar lying below the types.

10 While I have illustrated herein extremely simple means for effecting the necessary substantially uniform reduction in cross-section of an unjustified type-bar to produce therefrom a proper elongated or justified type-bar, it is of course to be understood that in actual practice a suitably-organized mechanism will be employed for the purpose, and such an organized mechanism, while not 15 illustrated or described herein, is shown, described, and claimed in a companion application, filed by me April 9, 1900 Serial No. 12,164. There is a further feature embodied in the practice of the present method of 20 justification which results in certain advantages. In some methods of justifying the spaces between types are altered and often-times made to differ in width for the purpose of filling out the line of composition with the result that the printed composition 25 when printed as a whole presents to the eye a broken, discontinuous form in which the wider blank-spaces are unpleasingly prominent and bear too great a proportion to the mass of the printed characters. In carrying 30 the present method into effect, however, it is evident that while these type-separating spaces are made wider they are all widened together in like proportion, and, moreover, the spaces between the lines are diminished 35 as a result of the reduction in thickness of the bars. Thus, though the blank-spaces are increased in one direction they are all uniformly increased, and this increase is compensated for, in so far as its effect on the 40 eye is concerned, by a corresponding diminution in another direction, and the printed matter obtained from an assemblage of type-bars justified according to the present 45 method, preserves, therefore, a homogeneous, uniform and pleasing effect.

Having described my invention, I claim—

1. The method of justifying an unjustified type-bar having thereon a line of types, which consists in uniformly elongating the 50 unjustified type-bar throughout its length by reducing the cross-section of the body of the bar.

2. The method of justifying an unjustified type-bar having thereon a line of types, which consists in uniformly elongating the 55 unjustified type-bar by subjecting the body of the bar to compression substantially throughout its length and thereby reducing the cross-section of the bar.

3. The method of justifying an unjustified type-bar having on one edge thereof a line of types, which consists in subjecting the body of the unjustified bar to compression substantially throughout its entire length and thereby reducing the cross-section of the bar substantially uniformly and elongating the bar. 65
4. The method of justifying an unjustified type-bar having thereon a line of types, which consists in rolling the body of the bar from end to end of the line and thereby elongating the latter. 70
5. The method of justifying an unjustified type-bar having thereon a line of types, which consists in rolling the body of the bar to a uniform reduced cross-section throughout to thereby elongate the bar. 80
6. The method of justifying an unjustified type-bar having thereon a line of types separated by transverse spaces, which consists in rolling the body of the bar below the bases of the types only and thereby elongating the bar and reducing the cross-section of the body of the bar below the base-line of said types. 85
7. The method of justifying an unjustified type-bar having on one edge thereof a line of types separated by transverse spaces in the edge of the bar, which consists in rolling the sides of the body of the bar below the bases of the types only and thereby reducing the cross-section of the body of the bar below the base-line of said types and elongating the bar. 90
8. The method of justifying a type-bar having thereon a line of type, which consists in modifying the cross-section of the type carrying body of the bar substantially uniformly throughout its length to thereby elongate the bar. 100
9. The method of justifying a type-bar having thereon a line of type separated from one another by spaces extending to the base lines of the bodies thereof, which consists in modifying the cross-section of the entire body of the bar below said base lines substantially uniformly throughout the length of the bar to thereby elongate the bar. 110
10. The method of justifying a type-bar having thereon a line of type separated from one another by spaces extending to the base lines of the bodies thereof, which consists in modifying the cross-section of the entire body of the bar below said base lines substantially uniformly throughout its length and thereby elongating the unjustified type-bar. 115
11. The method of justifying an unjustified type-bar having thereon a line of types separated from one another by spaces extending to a common base line of the bodies thereof, which consists in modifying the cross-section of the entire body of the bar 120
- 125

below said common base line substantially uniformly throughout its length, and thereby elongating the unjustified bar.

12. The method of justifying an unjustified type-bar having thereon a line of type separated from one another by spaces extending to the base lines of the bodies thereof, which consists in modifying the cross-section of the entire body of the bar below 10 said base lines substantially uniformly throughout its length without distorting said types, and thereby elongating the unjustified typebar.

13. The method of justifying an unjustified type-bar having thereon a line of type separated from one another by spaces extending to the base lines of the bodies thereof, which consists in modifying the cross-section of the entire body of the bar below 20 such base lines substantially uniformly throughout its length, thereby increasing the widths of said spaces and elongating the unjustified type-bar without distorting the types.

25 14. The method of justifying an unjustified type-bar having thereon a line of types the faces whereof are of less dimension in height than the dimension of the thickness of the bar, which consists in elongating the 30 unjustified type-bar by reducing the dimension of the thickness of the body thereof substantially uniformly throughout its entire length.

15. The method of justifying an unjustified type-bar having thereon a line of types, the faces of which are of less height than the thickness of such unjustified bar, which

consists in rolling the bar and thereby elongating the line of types.

16. The method of justifying an unjustified type-bar having thereon a line of types separated by transverse spaces, the dimensions of the height of the face of each type being less than the dimension of the thickness of said bar, which consists in rolling 45 the body of the bar below the bases of the types and thereby elongating the bar and reducing the cross-sectional thickness of the type carrying portion of the body of the bar below the base line of the types but not to a 50 thickness of a less dimension than that of the height of the types.

17. That improvement in the art of type-bar justification which consists in uniformly reducing the thickness over the entire length 55 of the type carrying body of each of a series of typebars, having thereon a line of type, and effecting the elongation thereof to a standard length, and also thereby uniformly increasing the spaces upon each bar throughout the length thereof.

18. That improvement in the art of type-bar justification which consists in uniformly reducing the thickness over the entire length 65 of the type carrying body of a typebar, having thereon a line of type, and effecting the elongation thereof and also thereby uniformly increasing the spaces throughout the length of the bar.

FRANCIS H. RICHARDS.
